UNITED STATES PATENT OFFICE.

JOHN H. PENDLETON, OF BROOKLYN, AND ANDREW BRYSON, JR., OF NEW YORK, ASSIGNORS TO THE RAPID TRANSIT CABLE COMPANY, OF NEW YORK, N. Y.

CABLE-RAILWAY STRUCTURE.

SPECIFICATION forming part of Letters Patent No. 406,302, dated July 2, 1889.

Application filed April 11, 1889. Serial No. 306,837. (No model.)

To all whom it may concern:

Be it known that we, JOHN H. PENDLETON, of Brooklyn, in the county of Kings and State of New York, and ANDREW BRYSON, Jr., of 5 the city and State of New York, have invented an Improvement in Cable-Railway Structures, of which the following is a specification.

This invention is made with special reference to the use of two traveling cables with 10 each track, one cable going faster than the other, or else one cable remaining in position ready for use in case of injury to the other cable, or both cables may be moving at the same speed and at the same time, so that a 15 portion of the cars may be connected with one and another portion with the other cable, to divide the work between them when the travel is heavy.

This invention is a modification of that set 20 forth in our application Serial No. 280,653, filed July 21, 1888, and we remark that the apparatus made use of for gripping one cable or the other can be similar to that shown in our application Serial No. 303,892, filed March 25 19, 1889, whereby the gripping apparatus can be changed from one position to the other for seizing and being acted upon by either of the cables.

In the drawings, Figure 1 is a plan of a portion of the straight track where the same is united with a curved track, and Fig. 2 is a similar view of a portion of a curved track. Fig. 3 is an elevation of the cable-supporting wheels and a cross-section of the track and a portion 30 of the elevated structure supporting such track, and Fig. 4 is a similar view representing the car-wheels and a portion of the car-platform and of the cable-supporting wheels connected with the gripping apparatus. Fig. 45 5 is a plan view, and Fig. 6 is a cross-section representing the cable-guide wheels in pairs.

The two cables are represented at G G', and the car-wheels are shown at a', Fig. 4, and a portion of the transverse moving platform is 45 shown at B' as below the main platform A, and upon this transverse moving platform B' are the cable-wheels D D', supported by the swinging bearers E E', as in our aforesaid application Serial No. 303,892, and it is to be understood that this transverse moving platform 50

B' can be shifted to bring the cable-gripping mechanism and the wheels D D' into line for receiving either cable G or G'.

In the straight portion of the road the cross-ties a a rest upon and are supported by the 55 girders b b' or their beams h h', and the track-rails c c' and the rail d are provided, as seen in Figs. 3 and 4, upon the cross-ties, and the usual guard-rails e are outside of the track-rails c c', and upon curves we make use of the 60 inner guard-rail e' within the convex or outer rail c of the track.

Upon reference to Figs. 1 and 2 it will be seen that the introduction of the inclined guide-pulleys i at intervals along the track 65 renders it necessary to omit one cross-tie at each pulley, and instead of using a tie that goes entirely across the short ties a' are employed. These short ties rest upon the girders or beams, and they are bolted upwardly to the 70 inner guard-rail e'; hence the track-rails c are properly supported by these short ties a' and the inner guard-rails e', that strengthen and support such short ties a'.

Upon the straight track, Fig. 1, where the 75 cable-wheels n² are introduced, the short ties a' are similarly supported by the inner guard-rails e', the outer guard-rails e in all instances being bolted to such short ties a' and aiding in their support. 80

Where the inclined guide-pulleys i are made use of, it is preferable to provide the beams h h' upon the girders b b' and between the same and the cross-ties, in order that there may be openings through such beams h at the places 85 occupied by the guide-pulleys i, as indicated in Figs. 3 and 4. These inclined guide-pulleys i are upon inclined shafts i⁴, that are supported by bearings i³ and i⁵, the latter being upon a cross-beam i² between the girders b b', 90 and these parts are similar to those set forth in our application Serial No. 280,653, and we also provide the strengthening-bar c² between the guard-rail e and the track c', and a similar bar c² between the track-rail c' and the metal 95 guard-rail d, and these strengthening-bars c² c³ are long enough to extend across the space occupied by the inclined guide-pulley and to rest upon the contiguous cross-ties, and these bars c² c³ and the respective rails c' d and 100

guard-rails e are bolted together by bolts c^4 , and render the track sufficiently strong to allow for the omission of one cross-tie where the guide-pulley i is introduced.

- 5 The standing rails n^7 , supported by the brackets a^3 , are made use of, in connection with the horizontal wheels n^8 upon the frame of the car, for resisting the lateral strain upon the car by the cable as the car passes around 10 the curve. These standing rails n^7 are upon the concave side of the curved track, because the lateral strain by the cable tends to draw the car transversely toward such standing rails.
- 15 In constructing the track upon a curve the outer rails c require to be sufficiently elevated to counteract the centrifugal force of the moving train. To accomplish this object, we introduce the wedge-shaped ties a^2 upon the 20 cross-ties a a' , as seen in Figs. 3 and 4, and we sometimes make use of the guide-pulleys n , adjacent to each inclined pulley i , such guide-pulleys n being grooved and having upwardly-inclined or conical surfaces toward the 25 inclined pulleys i , so that the cable will be guided up into the groove of the inclined pulley i as the car and its gripping mechanism pass along over the curved portion of the track; and we remark that the position of the gripping 30 mechanism and of the cable-wheels D D' is indicated in Fig. 4, and it will be apparent that the cable cannot escape from the groove of the inclined guide-pulleys i as the car and grip pass along, because the top edge 35 of the inclined guide-pulley i is nearly as high as the top of the cable when held by the grip, and the cable-wheels D D' and the guide-pulleys n prevent the cable dropping too low; hence such cable is reliably guided into position 40 as the car moves around the curve. These guide-pulleys n are sustained in suitable bearings o o , that project out from the adjacent cross-ties a .

The foregoing description is applicable to 45 both ranges of inclined pulleys i and guide-pulleys n , made use of with the two cables G and G' ; but upon reference to the drawings it will be apparent that the inclined pulleys i , that are provided for the cable G , occupy a different 50 position from those made use of with the cable G' . The inclined pulleys i for the cable G are entirely between the girders b b' and beams h h' , while the inclined pulleys made use of with the cable G' pass into openings 55 provided in the beams h' , as before described, and upon the curved portion of the track the inclined pulleys for the cable G usually alternate with the inclined pulleys for the cable G' , so that these inclined guide-pulleys i can 60 be of the proper size for supporting the cables and lessening the friction due to the strain upon such cables as they pass around the curve. We have represented in Fig. 3 a portion of the columns and of the girder cross- 65 ing the street in the elevated structure. These parts being of usual character do not require description.

In our aforesaid application, Serial No. 280,653, we have shown one range of guide-wheels applied at the curved portion of the 70 railway-track; but we have experienced difficulty in arranging for two cables around the curved portion of the track, because if horizontal wheels are made use of on vertical axes the wheels have to be small to allow for their 75 introduction between the tracks, and as the distance between the tops of the track-rails and the wheel-axes of the car is limited the difficulty of providing for two cables is augmented, and especially in view of the fact 80 that if two sets of horizontal guide-wheels were made use of the cable-grip would come in contact with one set of the guide-wheels when acting with the cable upon the other set of guide-wheels. We are enabled to overcome 85 these difficulties by our present improvements, because the second set of guide-wheels being at an inclination there is a V-shaped opening between one cable and the other, in which the grip mechanism can pass 90 as the car travels around a curve, and it will be apparent that although it is preferable to place both sets of guide-wheels at an inclination, because such wheels can be made larger than it is possible to employ when any of the 95 guide-wheels are horizontal, if the set of guide-wheels nearest to the outer or convex side of a railway-track are at an inclination, as shown, there is a space between the cable G , carried by such guide-wheels, and the guide-wheels and cable G' that are nearest the inner or concave side of the track, in which 100 there is room for the passage of the gripping mechanism when acting upon the cable G' that is nearest the inner or concave side of 105 the track, and for this reason it would be possible, but not preferable, to make use of small horizontal rollers upon vertical axes between the cable G' and the concave side of the track when the guide-wheels for the other cable G are at an inclination. It is generally 110 preferable to place these guide-wheels alternately, as shown in Fig. 2; but they might be placed in pairs, as seen in the plan, Fig. 5, and in the vertical section, Fig. 6, in which 115 case the one guide-wheel that passes beneath the other guide-wheel of each pair is preferably the smallest, as represented.

In some cases the cable vibrates up and down to the rear of the grip as such grip and car is pulled around the curve by the cable, and this vibratory movement of the comparatively slack cable may under some circumstances prevent the cable drawing properly 120 into the grooved periphery of the guide-wheel i , and in addition to this difficulty, from the vibration of the cable two trains may be sufficiently near each other for the cable to be 125 lifted by the tension between one grip and the other. To overcome this difficulty sometimes arising as aforesaid, we make use of the stationary inclined shields S^4 , in the form of arches extending across from one cross-tie a to the other and above the upper edge of 130

the grooved pulley *i*, and the faces of these shields *S⁴* are inclined and upon the line, or nearly so, of the inclined surface of the pulley *i*, as indicated in Fig. 6, so that the shield 5 directs the cable properly into its groove in the pulley, and should the cable in its motion come into contact with the inclined edge of the shield it will ride up against the same and slip off and pass down into the groove of 10 the pulley without injury to the cable or the shield.

We have represented inclined lifters *S⁵* in Figs. 5 and 6, which inclined lifters are in the form of segments of cylinders with flanges at 15 the ends resting upon the cross-ties *a*, and these lifters are placed in such a position in relation to the cable-pulleys *i* that the upper edges of the lifters coincide, or nearly so, with the under edge of the cable-pulley adjacent 20 to the point of contact therewith of the cable, and these lifters are adapted to take the places of the conical rollers *n*.

We claim as our invention—

1. The combination, with the elevated-railway structure and the inclined pulleys *i*, of cross-ties *a*, short ties *a'*, adjacent to where the inclined pulleys *i* are introduced, the outer guard-rails *e*, and inner guard-rails *e'*, to which the cross-ties and short ties are bolted 30 for holding the short ties in position, substantially as set forth.

2. The combination, in an elevated-railway structure having straight and curved tracks, of two cables occupying different positions 35 between the rails, and the inclined guide-pulleys upon the curved portion of the track for the respective cables, and the short ties *a'*, bolted to the guard-rails and adjacent to the guide-pulleys, substantially as set forth.

40 3. The combination, in an elevated-railway structure, with two cables occupying different positions between the track-rails, of supporting-pulleys for the two cables, such supporting-pulleys being in line, or nearly so, 45 with the short ties *a'*, such short ties being supported by and bolted to the guard-rails, substantially as set forth.

4. The combination, with the railway structure and two cables between the rails 50 of such structure, of two sets of guide wheels or pulleys, one set for each cable, the guide-

wheels at the curved portions of the track that receive the cable nearest the convex side of the track being at an inclination to pass down below the guide-wheels that support 55 the cable at the concave side of the track, substantially as set forth.

5. The combination, with the railway structure and two cables between the rails, of two sets of guide wheels or pulleys in 60 pairs, both guide-wheels being upon inclined axes and one guide-wheel of each pair of guide-wheels passing partially beneath the other guide-wheel of the pair, substantially as set forth. 65

6. The combination, with the railway structure and the cable, of an inclined guide-wheel for the cable and an inclined shield in the form of an arch extending over the upper edge of the inclined guide wheel or pulley 70 and secured at its ends to the railway structure, substantially as set forth.

7. The combination, with the railway structure and the cable, of inclined guide-wheels and stationary inclined lifters formed 75 as segments of cylinders, and supports at the ends of said lifters connected with the railway structure, substantially as set forth.

8. The combination, in a railway structure, with the track-rails and guard-rails, of 80 a standing rail at the concave side of the track, supports for sustaining such rail upon the cross-ties, and a horizontal wheel connected to the car and rolling against said rail to sustain the car against the lateral strain of 85 the cable as such car is traveling around the curve, substantially as specified.

9. The combination, with the railway structure having cross-ties *a*, track-rails *c c'*, and guard-rails *e e'*, of the standing rail *n⁷* 90 at the concave side of the track, and the brackets *a³*, for supporting such rails *n⁷*, and bolts for connecting the brackets to the cross-ties and the guard-rail, substantially as set forth.

Signed by us this 8th day of April, 1889.

J. H. PENDLETON.
ANDREW BRYSON, JR.
